SETBACK SWITCH

Thomas M. Perry, Bennington, Vt., assignor to
the United States of America, as represented
by the Secretary of the Navy

Application April 28, 1943; Serial No. 484,908

5 Claims. (Cl. 200—52)

1.

This invention relates to switches, and more particularly to setback switches which are adapted to be mounted in explosive projectiles for closing at least a portion of an electrical detonating circuit.

The prior art devices of this nature have been dependent upon operation by movement of numerous mechanical parts. Many of these mechanical parts must be precision made and interfitted in a comparatively small space. Therefore, it has required much time and skill to manufacture setback switches, and the expense involved has been relatively high. Also, the setback switches of the prior art have usually been dependent upon a single point of contact, which point of contact, for some reason, on others, has occasionally failed to close the electrical circuit.

An object of this invention is to provide a setback switch which may be mounted in explosive projectiles to maintain an electrical detonating circuit opened until the projectile has been fired, after which the acceleration of the projectile, creating a setback force, will actuate the switch to close the circuit.

Another object of the invention is to provide a setback switch wherein a plurality of contacts will be made, any one of which will close at least a portion of an electrical detonating circuit.

Another object of the invention is to provide a setback switch which is extremely simple in operation, positive in function, and wherein precision made mechanical parts are eliminated.

Other objects of the invention will appear after an inspection of the following description.

In the drawings:

Figure 1 is a vertical sectional view of the invention, showing the same mounted within a portion of an electrical detonating circuit, the switch being in opened position;

Figure 2 is a vertical sectional view of the invention showing the position of the parts when the switch has been closed by the force of setback created when the projectile is fired;

Figure 3 is a perspective view of an electrical contact sleeve;

Figure 4 is a perspective view of the collapsible contact element; and,

Figure 5 is an inverted perspective view of the plunger.

Referring now to the drawings, and particularly to Figure 1 thereof, it will be seen that the switch which forms the subject matter of this invention is adapted to be mounted in an electrical detonating circuit C, the circuit having a proximity fuze and a source of current B incorporat-

2.

ed therein. The numeral 10 indicates the body of the device, which is formed of suitable insulating material, and may be a portion of a body of an amplifier or other component within the projectile. A bore 11 extends through the body 10 and has a restricted portion 12 at its rear or lower end. A cylindrical contact sleeve 13, which is formed of tubular copper or other suitable conductive metal, is press fitted or otherwise securely mounted within the bore 11. Wire 14, which forms one side of the electrical circuit C, is soldered or otherwise secured to the cylindrical contact member 13 at 15. Wire 16, which forms the other side of the electrical circuit C, is mounted through the restricted opening 12 of bore 11 and is securely held or anchored therein by a sleeve 17, the sleeve 17 being press fitted within the restricted opening 12.

A semi-resilient flexible metallic contact wire 18 is secured to wire 16 by soldering 19. The contact wire 18 extends axially. The contact wire 18 will normally remain in the position as shown in Figure 1, due to its own semi-resilience, but it is sufficiently ductile so that it may be easily compressed or deformed into flexible engagement with the surrounding sleeve 13, and will remain in its deformed position. A plunger 20, preferably formed of insulating material, is positioned within the contact sleeve 13, and has a relatively loose fit therein. However, the frictional engagement between the plunger 20 and the cylindrical contact sleeve 13 is sufficient to prevent longitudinal movement of the plunger within the sleeve under all normal handling conditions of the projectile. When the projectile is fired, the acceleration thereof creates sufficient setback force to cause the plunger 20 to slide rearwardly within the sleeve 13, toward the restricted portion 12 of bore 11.

The plunger 20 is provided with an axially positioned bore 21 forming a pocket which extends from the rear of the plunger forwardly, but terminates short of the forward end thereof. The rear or lower end of bore 21 has an outwardly flared portion 22. It will be apparent by one skilled in the art that the form of the flared portion 22 may be varied from that disclosed; and, obviously, the form will depend primarily upon the length of the bore 21 within the plunger 20, the length of the contact wire 18 and the diameter of contact sleeve 13.

The operation of the device will be readily understood from the foregoing description. The plunger 20 is positioned within the contact sleeve 13 so that the contact wire 18 will extend within

the bore 21 of plunger 20. When the parts are in this position, as shown in Figure 1, the circuit is broken because of the space between contact wire 18, which forms an extension of one side of the circuit, and contact sleeve 13, which forms an extension of the other side of the circuit. When the projectile is fired, the setback force created by the acceleration of the projectile forces the plunger 20 rearwardly. As the plunger moves rearwardly, the contact wire 18 will bend and assume the position as shown in Figure 2. When in this position, the wire 18 will make a plurality of contacts with sleeve 13, thus closing the circuit C. In case of reverse setback, occasioned by the projectile striking an object after being fired, the plunger 20 will move forwardly, but in view of the fact that the wire 18 is not directly connected to the plunger 20, the forward movement of the plunger will not affect the wire 18, and the latter will remain in its collapsed position, thus maintaining circuit C closed. It will be understood that while three points of contact are shown between wire 18 and sleeve 13, a larger or smaller number of contacts may be obtained by varying the length of wire 18 or its resilience, varying the diameter of sleeve 13, or varying the length of bore 21 and/or the shape of the flared portion 22 thereof.

From the foregoing description, it will be seen that the subject matter of this invention is extremely simple in operation and positive in function, and that it can be easily and cheaply made and assembled.

One of the particular advantages of my improved setback switch is that it will not be operated by repeated small shocks. That is to say, if the switch is jarred it will be reset to its normal inoperative condition by the action of the spring wire 18, which will move the plunger 20 to its original position.

It is also desired to point out that my improved switch may be easily short-circuited for the purpose of testing a complete circuit in which the switch may be wired.

I claim:

1. A setback switch adapted to be mounted within a projectile to close at least a portion of an electrical detonating circuit upon the application of setback force created when the projectile is fired comprising a body member, a bore in said body member, an electrical contact sleeve positioned within said bore, elongated bendable contact means mounted in said body member and extending within said contact sleeve in spaced relation thereto, and a plunger positioned within said sleeve capable of sliding therein upon the application of setback force for bending said elongated contact means into a plurality of contact engagements with said contact sleeve.

2. A setback switch adapted to be mounted within a projectile to close at least a portion of an electrical detonating circuit upon the application of setback force created when the projectile is fired comprising a body member, a bore in said body member, an electrical contact sleeve positioned within said bore, a wire mounted in said body member and extending within said contact sleeve in spaced relation thereto, and a plunger positioned within said sleeve capable of sliding therein upon the application of setback force for bending said wire to make a plurality of contacts between said wire and said contact sleeve.

3. A setback switch adapted to be mounted

within a projectile to close at least a portion of an electrical detonating circuit upon the application of setback force created when the projectile is fired comprising a body member, a bore in said body member, an electrical contact sleeve positioned within said bore, a plunger positioned within said sleeve capable of sliding therein upon the application of setback force, a bore in said plunger, and a wire mounted in said body member and extending axially within said contact sleeve in spaced relation thereto and having a portion thereof extending into said bore in said plunger, the sliding movement of said plunger within said sleeve causing said wire to bend and make a plurality of contacts with said contact sleeve.

4. A setback switch adapted to be mounted within a projectile to close at least a portion of an electrical detonating circuit upon the application of setback force created when the projectile is fired comprising a body member of insulating material, a bore in said body member, an electrical contact sleeve positioned within said bore, a plunger positioned within said sleeve capable of sliding therein upon the application of setback force, a bore in said plunger having an outwardly flared portion at its outer end, and a wire mounted in said body member and extending within contact sleeve in spaced relation thereto and having a portion thereof extending into said bore in said plunger, the sliding movement of said plunger causing said wire to bend outwardly to make a plurality of contacts with said contact sleeve.

5. A setback switch adapted to be mounted within a projectile to close at least a portion of an electrical detonating circuit upon the application of setback force created when the projectile is fired comprising a body member of insulating material, a bore extending through said body member, said bore having a restricted portion at its lower end, an electrical contact sleeve positioned within said bore, adapted to be connected to one side of the electrical detonating circuit, a plunger positioned within said sleeve capable of sliding therein upon the application of setback force, a bore having an outwardly flared portion in said plunger, and a wire mounted in said body member extending axially within said contact sleeve in spaced relation thereto, and having a portion thereof extending into said bore in said plunger, said wire entering the body member through the restricted portion of said bore, and forming an extension of the other side of the electrical detonating circuit, the sliding movement of said plunger causing said wire to bend outwardly to make a plurality of contacts with said contact sleeve.
